UNITED STATES PATENT OFFICE.

HENNING HALLSTREAM, OF BROCKTON, MASSACHUSETTS, ASSIGNOR TO CROSS PAPER FEEDER COMPANY, OF PORTLAND, MAINE, A CORPORATION OF MAINE.

PAPER-FEEDING MACHINE.

1,246,264.

Specification of Letters Patent.

Patented Nov. 13, 1917.

Application filed March 9, 1917. Serial No. 153,714.

To all whom it may concern:

Be it known that I, HENNING HALLSTREAM, a citizen of the United States, residing at Brockton, in the county of Plymouth 5 and State of Massachusetts, have invented certain new and useful Improvements in Paper-Feeding Machines; and I do hereby declare the following to be a full, clear, and exact description of the invention, such as 10 will enable others skilled in the art to which it appertains to make and use the same.

The invention relates to that class of paper feeding machines in which a bank of feathered or fanned out sheets is fed to 15 combing wheels or other sheet separating devices which separate the sheets and advance the top sheet so that it may be removed or presented to machines for further manipulating or acting upon it.

20 In paper feeding machines of the continuous type the bank of sheets is supplied to the feed table of the machine by a loader comprising an upper supply table on to which the sheets are loaded by the attendant, and a curved throat which inverts the bank and reverses its direction of movement as it passes from the supply table to the feed table. Under certain conditions it 25 may be desirable to maintain the supply of sheets by building on to the rear end of the bank on the feed table, instead of utilizing the loader, as, for instance, in feeding sheets which by reason of their small size, or for other reasons, may not pass properly 30 through the feed throat, and it is the object of the present invention to provide a construction which will enable this to be readily and conveniently done.

To this end the invention contemplates so 35 mounting the loader, and so constructing and arranging the bank feeding mechanism, that the loader may be moved into or out of operative relation with the bank feeding and sheet separating mechanisms. This enables the loader to be positioned to coöperate 40 with the bank feeding and sheet separating mechanisms in the usual manner, or to be moved back into position to give ready access to the bank on the feed table, and to 45 enable the attendant to readily build on to the rear end of the bank of sheets thereon.

The invention will be readily understood from an inspection of the accompanying drawings and the following detailed de-

scription of the mechanism illustrated there- 55 in.

In the drawings, Figure 1 is a side elevation showing so much of a continuous paper feeding machine as is necessary to illustrate the application of the present improvements 60 thereto, and Fig. 2 is a detail sectional view on line 2 of Fig. 1.

In the drawings the invention is illustrated as embodied in the automatic paper feeding machine known as the "Cross paper 65 feeder." In this machine the sheet separating devices comprise two combing wheels 1 arranged on opposite sides of the medial line of the feed table 2, and independently controlled by mechanism which is more fully 70 illustrated and described in Patent No. 812,260, February 13, 1906. The combing wheels are lowered upon the front end of the bank of sheets supported on the feed table by cams carried on the cam shaft 3, 75 and are raised independently by cut-out mechanism controlled by the trips 4. When the combing wheels are lowered, they act to separate and advance the top sheets of the bank, until the front edge of the top 80 sheet is advanced into position between the delivery rolls 5 and 6, when the sheet engages the trips 4 and throws into operation the cut-out mechanism to raise the wheels. The delivery rolls then act to carry away the 85 top sheet, after which the combing wheels are again lowered upon the bank. The second sheet is held during the removal of the top sheet by a clamping mechanism indicated generally at 7. 90

The bank of sheets upon the feed table rests upon feed tapes 8 which pass over pulleys secured to shafts 9 and 10, and are intermittently actuated to feed the bank to the combing wheels. The bank of sheets is supplied to the feed table by a loader comprising an upper supply table 11 and a feed throat 12 connecting the forward end of the supply table with the rear end of the feed table. The feed throat is formed by the feed drum 13 mounted at the forward end of the supply table and the curved guide fingers 14. The bank of sheets on the supply table rests upon the usual feed tapes 15, and the bank is pressed against the tapes and feed drum 100 13 by the usual pressure rolls 16. The feed drum, tapes and pressure rolls are actuated 105 to feed the bank through the feed throat,

and on to the tapes 8 of the bank feeding mechanism, by gearing 17 connecting the drum and pressure rolls with a gear 18 on the shaft 9.

5 In embodying the present invention in a machine having the construction thus far described, the side frames 19 of the loader are mounted to slide upon guide bars 20 at the sides of the machine, so that the 10 loader may be moved on the guide bars into position to give access to the rear part of the feed tapes 8, and to the parts which are normally rendered either inaccessible or inconvenient of access by the parts of the 15 loader. The gearing 17 is also preferably so arranged that it may be brought into and out of mesh with the gear 18 by movement of the loader. The mechanism for actuating the feed tapes 8 is also preferably so 20 constructed and arranged that it will not be affected by movement of the loader into and out of operative position. In the construction shown, the side frames 19 of the loader are provided with flanges 21 arranged to embrace the guide bars 20, and the upper edges of the bars are provided with rack teeth 22 which are engaged by pinions 23 formed on the ends of a shaft 24 mounted in the side frames. The ends of 25 the shaft 24 may be provided with projections or sockets 25 to receive a wrench or crank handle, so that the shaft may be conveniently turned to slide the loader back and forth on the guide bars.

30 35 The mechanism for actuating the tapes 8 of the bank feeding mechanism and the bank feeding parts of the loader is connected with the forward pulley shaft 10, so that it will not interfere with and will be unaffected by the forward and backward movement of the loader. This mechanism as shown is substantially the same in construction and mode of operation as the mechanism fully 40 shown and described in application Serial No. 11,941, filed March 4, 1915. It comprises a ratchet wheel 26 secured to the shaft 10, and operated upon by a pawl 27 carried by a lever 28. The mechanism for reciprocating the pawl carrying lever comprises a 45 driving lever 29 which is reciprocated by a crank 30 secured to the end of the cam shaft 3, and connected by a link 31 with the lever. Motion is transmitted from the driving lever to the pawl carrying lever through a driven 50 lever comprising two arms 32 and 33 secured to a rock shaft 34, the arm 33 being connected by an adjustable link 35 to the upper end of the pawl carrying lever. The arm 32 of the driven lever is provided with a lug 36 55 arranged to be engaged by the driving lever during its movement toward the right. The driven lever will therefore move with the driving lever to the end of its stroke in this direction. The means for connecting the 60 driven lever to move with the driving lever 65

during the stroke of the driving lever in the opposite direction consists of a sheet controlled latch 37 carried by the driven lever, and arranged to engage a notch 38 in the end of the driving lever. The latch is secured to the end of a rock shaft 39 mounted in the lower ends of the arms 32 and 33, and is moved in a direction to engage the driving lever by a spring coiled around the shaft. Movement of the latch in either direction is determined by stop lugs 40 formed on the arm 32, and arranged to straddle an arm 41 secured to the rock shaft 39. The arm 41 is connected to one end of a ratchet bar 42, the other end of which is arranged to slide through a rocking bearing 43. The upper surface of the ratchet bar is provided with a series of teeth 44 arranged to be engaged by a stop pawl 45 mounted on a rock shaft 46 which is provided with an arm 47. The end of the arm 47 is connected by a link 48 with a lever 49, which is in turn connected by a pin 50 with an arm 51, which forms a part of one of the cut-out mechanisms. With this construction, the driven lever and connected pawl carrying lever will move toward the left with the driving lever until the sheet operates the cut-out, when the pawl 45 will arrest the movement of the bar 42, and operate the latch 37 to disconnect the driven lever from the driving lever, and thus discontinue the forward movement of the driven lever and pawl carrying lever.

While it is preferred to employ the specific construction and arrangement of parts shown and described in embodying the invention in the "Cross paper feeder," it will be understood that this construction and arrangement is not essential to the broader features of the invention, and that the construction and arrangement of parts may be varied or modified as found desirable or best suited to the construction of the machine in which the invention is to be embodied.

Having explained the nature and object of the invention, and specifically described one form of mechanism in which it may be embodied, what is claimed is:—

1. A paper feeding machine, having, in combination, sheet separating mechanism, bank feeding mechanism, and a loader mounted for movement into and out of operative relation to the bank feeding and sheet separating mechanisms.

2. A paper feeding machine, having, in combination, a feed table, sheet separating mechanism, bank feeding mechanism, a loader, and guides on which the loader is mounted to slide into position to deliver a bank of sheets to the bank feeding mechanism or into position to permit manual supply of sheets to the rear of the bank on the feed table.

3. A paper feeding machine, having, in combination, sheet separating devices, a

- feed table, bank feeding tapes passing over the feed table, forward and rear tape carrying shafts, feeding mechanism applied to the forward tape shaft, a gear on the rear tape shaft, a loader mounted for backward and forward movement, and bank feeding devices on the loader including a gear arranged to engage and disengage the gear on the rear tape shaft.
- 5 4. A paper feeding machine, having, in combination, a feed table, feed tapes for feeding a bank of sheets over the table, combing wheels for acting on the forward part of the bank, a loader frame mounted for movement lengthwise of the bank into and out of operative relation to the feed tapes, a supply table and a curved guide throat on the loader frame, and bank feed-
- ing devices on the loader frame for feeding a bank from the supply table through the throat on to the feed table.
5. A paper feeding machine, having, in combination, a feed table, feed tapes for feeding a bank of sheets over the table, front and rear tape carrying shafts, sheet controlled actuating mechanism applied to the forward tape shaft, guide bars extending lengthwise of the feed table, a loader frame mounted to slide on the guide bars, a supply table and a curved bank reversing and inverting guide throat on the loader frame, and bank feeding devices on the loader frame arranged to be connected with and disconnected from the tape actuating mechanism.

HENNING HALLSTREAM.
